FURNACE DOOR FRAME CONSTRUCTION

Ottwin L. Braun, Pittsburgh, Pa., assignor to Reliance Steel Products Company, McKeesport, Pa., a corporation of Pennsylvania

Application July 27, 1956, Serial No. 600,423

3 Claims. (Cl. 110—172)

This invention relates to removable door frames for furnaces of the type used in the manufacture of steel, and particularly to locking means for securing the door frames to the front wall of a furnace of the type having a skewback channel.

Furnaces, such as open-hearth furnaces, are provided with a door opening to which is secured a water-cooled metal door frame, thus providing a cooperating frame for a movable water-cooled metal door. In such cases, the frame is usually set on a supporting ledge below the door opening in the furnace, and its upper end is removably secured to a horizontally-extending structural section above the door opening that is called the skewback channel. The door frames have to be serviced or replaced from time to time, requiring that the securing means be of a character which will permit removal and replacement.

There have been many methods of fastening door frames to the skewback channel, such as bolts, wedges and the like, which require considerable time to apply, and in addition such parts become deformed or mislaid when changing a door frame and must be replaced. In many cases the door frame is not held tightly against the face of the furnace, so that there is an opening through which flame may blow past the door frame, causing considerable damage to both the door frame and the edge of the opening.

The principal object of my invention is to provide a novel means of fastening the top of a furnace door frame to the front opening of an open-hearth furnace after the door frame has been properly positioned at the front of the furnace.

Another object is to provide a novel locking means of the above type carried by the door frame and a part of the furnace, such as a skewback channel, which will always be available and ready for use.

Another object is to provide a novel locking means of the above type which may be readily unlocked and withdrawn from an operating position without being completely detached.

Other objects will appear from the following detailed description of the invention when taken in connection with the accompanying drawings, wherein:

Fig. 1 is a front elevation of a water-cooled door frame for an open-hearth furnace, said door frame being modified to enable the practice of this invention;

Fig. 2 is an enlarged transverse section in the plane of line II—II of Fig. 1;

Fig. 3 is a plan view of another portion of the embodiment of this invention for cooperation with the portion shown in Fig. 2;

Fig. 4 is a side elevation, partly in section, of the parts shown in Figs. 2 and 3 arranged in cooperative relation;

Fig. 5 is a front elevation of the parts shown in Figs. 3 and 4; and

Fig. 6 is a side elevation of the portion shown in Fig. 3.

2

Referring to the drawings in detail, Fig. 1 shows a water-cooled door frame 1 of the usual type adapted to frame the front opening of an open-hearth furnace (not shown). Secured to the top edge of the door frame 1 by welding, shown generally as 2, or other suitable means, is a pair of arms 3 extending upwardly therefrom. These arms 3 have their back edges 4 straight, while a portion 5 of the front edge 6 is sloped or tapered upwardly and inwardly, as shown in Fig. 2, with the arms being narrower at the top.

Referring now to Fig. 3, an anchor or bracket member 7 is shown which comprises an upright support element 8 shaped in the form of a triangle with its apex at the top. This support element 7 is secured at its base to the top of a skewback channel 9 by means of a pair of horizontal, outwardly extending mounting lugs 10 and screw thread means indicated at 11 extending through slots 12 in said lugs. While I have shown the anchor member 7 mounted on the skewback channel 9, which is a part of the furnace wall, it should be understood that any other structural member that may extend horizontally across the front of the furnace from one buckstay to the other will serve for the purpose of this invention. It must, however, be a metallic member integrated in the front wall of the furnace at an elevation even with or slightly above the top of the door frame 1.

Secured by welding, or other suitable mounting means, to the middle of the front side of the triangular support member 8 is an upright carrier element or web 13, which is provided with a vertical slot 14, in which a pin 15 of a link member 16 is slidably and rotatably received. The link comprises two bars 17 secured at their inner ends to opposite ends of the pin 15 by welding, or other means, which thus bracket the carrier element 13. The outer ends of the bars 17 are secured in a similar manner to a cross pin 18, which may be identical to pin 15, completing the loop or closing the link member 16. The link member 16 is thus rotatably and slidably mounted for vertical and rocking movement in the carrier member 13.

The carrier element 13 is further provided at its top surface with a semi-circular recess or notch 19 having its axis in a transverse direction and parallel to the axes of the pins 15 and 18. This recess 19 provides a cavity (Fig. 6) for the pin 15 when the link 16 is swung upwardly to a vertical position out of the area of action. Thus the link member 18 may be retained in a position where it does not interfere with other operations and is always available for locking the top of the furnace door frame 1 in its mounted position.

When the opening in the front of the furnace is to be framed, the door frame 1 is swung into position on top of a sill or ledge, by hooking onto a loop member 20 secured to the top of the door by any suitable means (not shown) with the top of the door abutting the skewback channel 9 and the sloped surface 5 of the arms 3 facing outwardly opposite the locking means 7 as shown in Fig. 4. Each link member 16 is then moved upwardly, carrying pin 18 upwardly out of its recess 19 and pin 15 upwardly in the slot 14, and then the upper end of the link member 16 is swung outwardly and rocked in a counter-clockwise direction until pin 8 engages the tapered surface 5. The link members, being of such sturdiness as to withstand hammering, are then hammered downwardly at both ends until they assume positions the same as, or similar to, the one shown in Fig. 3. In this position the top of the door frame is held firmly and securely against the outer face of the skewback channel 9, thereby sealing off any blowing of flame past the edge of the door frame. The most desirable position of the carrier elements 13 relative to the cams 3 may be obtained by

loosening screw thread means 11, shifting carrier member 13 to the desired position, and then retightening the screw thread means.

It will thus be seen from the foregoing that my invention provides a novel means which may be readily put out of the way when not in use, and yet kept ready and available for use when needed, and when in use provides novel means for securing the furnace door frame in position for engaging the furnace door and maintaining at all times a tension which holds the frame tightly against the face of the furnace. 10

I claim:

1. In the construction of the front wall of a furnace having a skewback channel therein and a door frame adapted to be removably mounted against said skewback channel in said front wall, a locking means for securing said door frame against said skewback channel comprising a pair of laterally spaced, upwardly extending rigid arms secured to the top of said door frame and having their outer surfaces tapered inwardly with the narrowest width at the top, a pair of upwardly extending anchor members secured to said skewback channel above the level of the top of said door frame, each of said anchor members having a vertical slot therein, and a link means movable vertically in the slot and slidably engaging the tapered surface of one of said arms to thereby draw said door frame into sealing contact with said skewback channel as said link means is forced downwardly in said slots and over the tapered surfaces of said arms. 15

2. The construction of a furnace wall as described in claim 1 wherein each of the anchor members is provided at its top with an upwardly opening recess for re-

ceiving that portion of the link means which normally engages the tapered surfaces of said arms and retaining said portion therein when not in use.

3. A furnace construction comprising a skewback channel, a door frame having a top and depending legs with the top facing against the skewback channel, a plurality of upwardly-extending arms on the top of the frame spaced from one another, a corresponding number of brackets on the top edge of the skewback channel spaced along the channel to correspond to the spacing of the arms, and loop-forming links secured to the brackets pivotally and vertically movable with respect to the brackets into and out of position where they loop over the respective arms to releasably hold the top of the frame against the channel, said brackets having a vertical web which is normal to the plane of the face of the skewback channel, said web having a vertical slot therein and having a transverse notch in the top edge above the slot, the link having a transverse pin at one end engaged in the slot and a transverse pin at its other end which may be rested in the notch when the link is vertical and which is engaged across the outer face of the arm on the door when the link is in a normal horizontal operating position. 20
